UNITED STATES PATENT OFFICE.

ANNA GUTH, OF NEW YORK, N. Y.

CURTAIN-POLE.

1,324,591.

Specification of Letters Patent.

Patented Dec. 9, 1919.

Application filed June 7, 1919. Serial No. 302,464.

To all whom it may concern:

Be it known that I, ANNA GUTH, a citizen of the United States, and residing at New York, in the county of New York and State 5 of New York, have invented certain new and useful Improvements in Curtain-Poles, of which the following is a specification, such as will enable those skilled in the art to which it appertains to make and use the 10 same.

This invention relates to curtain poles, drapery holders and the like, and the object thereof is to provide an improved device of this class which is simple in construction 15 and attractive and ornamental in appearance, and with which curtains, draperies and like articles may be suspended therefrom in a simple and efficient manner.

The invention is fully disclosed in the 20 following specification, of which the accompanying drawing forms a part, in which the separate parts of my improvement are designated by suitable reference characters in each of the views, and in which:—

25 Figure 1 is a side and sectional view of my improved holder with part of the construction broken away;

Fig. 2 a transverse section of the device as shown in Fig. 1 and indicating the method 30 of suspending an article therefrom;

Fig. 3 a view similar to Fig. 1 showing only a part of the construction and showing a modification; and,

Fig. 4 an end and sectional view of the device shown in Fig. 3.

In Figs. 1 and 2 of the drawing I have shown my improved curtain pole or drapery holder which consists of a bar member *a* preferably composed of wood or similar fibrous 40 material, and one side face of which is provided with a central longitudinal groove *a*². Mounted on the bar member *a* is a sheet metal covering *b* which extends the full length of said bar, and the ends *b*² of which 45 are bent into the longitudinal groove *a*² in the bar *a*, as clearly shown in Figs. 1 and 2. The ends of the bar *a* are provided with sheet metal caps *b*³ secured thereto by tacks, 50 nails or screws *b*⁴, and said caps are provided in one side thereof with recesses *b*⁵ which correspond with and which are in alignment with the groove *a*² in the bar *a*.

Placed in and secured in the longitudinal groove *a*² is a strip *c* of cork or other suitable fibrous material and as shown in Fig. 55 2 a curtain, drapery or the like *d* may be suspended from the bar *a* by passing the upper end *d*² thereof around said bar and passing headed pins *e* therethrough and into the strip *c* of cork or similar material, and it will be understood that said bar *a* may be suspended from the top of a window 60 frame, doorway or the like by clamps or other devices placed thereon in the usual manner.

In Figs. 3 and 4 of the drawing, I have shown a slight modification which consists in providing the surface of the bar *a* with a plurality of longitudinal beads or grooves *a*³, and conforming the sheet metal covering 70 to said beaded and grooved portions to give corrugated or fluted appearance to the bar *a* when the sheet metal covering is applied thereto, and the perimeter of the cap plates *b*³ secured to the ends of said bar, only one 75 of which is shown in said figure, is formed to correspond with the corrugated or fluted construction of the bar *a*, and in this construction the ends of said sheet metal covering extend into the longitudinal groove *a*² 80 in the bar *a*, as in the construction shown in Figs. 1 and 2.

It will be understood that the bar *a* may be of any desired form and the sheet metal covering applied thereto may be formed to 85 produce any ornamental design or effect, and while I have described my improvement as a curtain pole or drapery holder, it will be understood that the same may serve as a picture molding, or the like, from which 90 pictures and other articles may be suspended, and changes in and modifications of the construction herein shown and described may be made, within the scope of 95 the appended claim, without departing from the spirit of my invention or sacrificing its advantages.

Having fully described my invention, what I claim as new and desire to secure by Letters Patent, is:—

In a device of the class described, a rectangular bar member provided in one side face thereof with a longitudinal groove or recess, a sheet metal covering extending en-

tirely around said member and the edges of which are inserted into said groove, said groove being adapted to receive a filling of cork or similar material and the ends of 5 said bar member being provided with metallic end caps.

In testimony that I claim the foregoing

as my invention I have signed my name in presence of the subscribing witnesses this 5th day of June, 1919.

ANNA GUTH.
